UNITED STATES PATENT OFFICE

2,565,559

VEGETABLE CLEANING TABLE AND
ROLLS THEREFOR

Herman R. Hurdelbrink, Shelbyville, Mich.

Application November 5, 1945, Serial No. 626,646

6 Claims. (Cl. 15—3.11)

1

This invention relates to improvements in vegetable cleaning table and rolls therefor.

The main objects of this invention are:

First, to provide a cleaning and grading means which effectively cleans vegetables, such as onions for example, without objectionable abrasion or without removing parts of the skin which it is desired to leave on the vegetables.

Second, to provide an effective means for cleaning onions which does not abrade or bruise the onions.

Third, to provide a cleaning machine which may be adjusted to meet varying conditions of the articles cleaned.

Objects relating to details and economies of the invention will definitely appear from the description to follow. The invention is defined in the claims.

A structure which embodies the features of the invention is clearly illustrated in the accompanying drawing, in which:

Fig. 1 is a fragmentary side elevation partially in longitudinal section of a machine embodying my invention especially designed for cleaning onions.

Fig. 2 is a plan view thereof, parts being broken away to show details.

Fig. 3 is an enlarged fragmentary view partially in transverse section on line 3—3 of Figs. 1 and 2.

Fig. 4 is an enlarged fragmentary view mainly in section on a line corresponding to line 4—4 of Fig. 3.

Fig. 5 is a fragmentary longitudinal section on line 5—5 of Fig. 3.

Fig. 6 is a view similar to Fig. 5 illustrating adjustments of the structure.

The embodiment of the invention illustrated comprises a main supporting frame 1 including pairs of uprights 2, 3 and 4, these being connected by cross pieces 5.

The cleaning means of my invention comprises side members 6 which are connected at their front ends by the cross piece 7, their rear ends being pivotally mounted on the transverse shaft 8. I provide a series of rollers 9 provided with shafts 10 projecting at the ends of the rollers and journaled in bearings 11 provided therefor in the side members 6. The shafts 10 project through one side member to receive the sprocket wheels 12.

The rollers 9 are provided with spiral grooves 13, the grooves of adjacent rollers being oppositely pitched. These grooves are of substantial depth and receive the resilient fins 14 which are

2

bound in the grooves by the wires 15. The fins are preferably formed of strips of rubber folded around the wires, the wires being drawn into the grooves and the ends of the wires secured in the end grooves 16 of the rollers. The fins are formed of rubber stock of substantial thickness and in practice I have used strips cut from inner tubes. Of course, they could be made of any suitable rubber or flexible material although resilient material is desirable. The fins project substantially from the surfaces of the rollers.

The rollers are driven in counterclockwise or rearward direction as viewed in Figs. 1, 5 and 6 and this may be accomplished by means of the flexible sprocket chain 17, the upper reach of which is held in engagement with the sprockets by means of the upper member 19 of the guard housing 20.

In the embodiment illustrated the motor 21 is mounted on the support 22 secured on the upper ends of the uprights 3. The drive connection to the shaft 8, which is provided with a driving sprocket not illustrated, comprises the pulley 23 connected by the belt 24 to the motor pulley 25. The shaft 26 of the pulley 23 is provided with a pulley 27 which is in turn connected to the pulley 28 of the shaft 8 by means of the belt 29. This driving arrangement drives the rollers at the desired reduced speed.

The front ends of the side members 6 are adjustably supported on the uprights 2 by means of the rods 30 which may be selectively engaged in the vertical series of holes 31. A feed chute 34 is provided at the front of the rollers, the onions or other articles to be cleaned being placed on this chute and advanced to the cleaning rollers as desired. The rollers are spaced so that the smaller onions, commonly called "pickling" onions, pass between them. The onions to be cleaned are tumbled and transferred from one roller to another of the series and effectively cleaned in this process, this without objectionable abrasion thereof and without removal of the skin which it is desired not to remove. In practice the rollers are preferably formed of sections as illustrated in Figs. 5 and 6. The sections may be readily milled and grooved at 32 to receive the shaft. This facilitates manufacture.

As the onions are conveyed or translated by the cleaning rollers they are discharged on to the grading screen 33 which in turn discharges to the grading screen 34. These grading screens are mounted for reciprocatory motion but this forms no part of my invention and is not described in detail. They are illustrated merely to show the

association of my cleaning mechanism with a suitable grading means.

The driven pulley 28 is controlled by means of the belt tightener lever 35 pivoted at 36 and provided with a suitable retaining segment 37, this lever carrying an idler pulley 39 coaxing with the belt 29 to apply driving tension thereto. The side members are provided with ledges 40 on their inner sides which overhang the ends of the rollers, preventing the onions or articles cleaned from being pinched against the side members.

By regulating the inclination of the cleaning rollers the structure may be adapted to meet varying conditions in use, that is, the greater cleaning action required, the greater the pitch of forward inclination should be, and in some conditions a horizontal position or even a rearward inclination might be desirable.

I have illustrated and described my invention in a highly practical embodiment thereof. I have not attempted to illustrate or describe certain modifications or adaptations which I contemplate as it is believed this disclosure will enable those skilled in the art to embody or adapt my invention as may be desired.

Having thus described my invention, what I claim as new and desire to secure by Letters Patent is:

1. In a root vegetable cleaning machine, the combination of a frame, a plurality of transversely disposed equally spaced closely adjacent rollers mounted in said frame in parallel noncontacting coplanar relation and provided with continuous spiral fins consisting of strips of soft resilient continuous material pitched axially of the rollers sufficiently to permit the vegetables to contact the rollers between turns of the fins, the fins of adjacent rollers being oppositely pitched and staggered in closely spaced nontouching relation, means for driving said rollers in the same direction and at the same speeds, and means for varying the inclination of the frame and the plane of said rollers transversely of the axes of the rollers.

2. In a vegetable cleaning machine, the combination of a frame, a plurality of transversely disposed rollers mounted in said frame in parallel relation and provided with continuous spiral fins consisting of strips of soft resilient continuous material folded longitudinally and secured to said rollers with their free edges projecting from said rollers, the fins of adjacent rollers being oppositely pitched, and means for driving said rollers in the same direction and at the same speeds, said rollers being spaced to support objects to be cleaned therebetween.

3. In a vegetable cleaning machine, the combination of a frame, a plurality of transversely

disposed rollers mounted in said frame in parallel relation and provided with continuous spiral fins consisting of strips of longitudinally folded resilient material, the fins of adjacent rollers being oppositely pitched, and means for varying the inclination of the frame.

4. In a machine for cleaning root vegetables, the combination of a frame, and a plurality of transversely disposed rollers mounted in said frame in adjacent parallel relation and provided with continuous spiral fins consisting of strips of continuous soft resilient material, the fins of adjacent rollers being oppositely pitched and disposed in closely spaced nontouching relation at their adjacent edges.

5. A roller for a vegetable cleaning machine comprising a cylindrical member having a spiral groove formed therein, a strip of soft resilient flexible material folded longitudinally and having the folded portion thereof positioned in said groove, and a wire positioned in the folded portion of said strip to hold said strip on said cylindrical member with the free edges of said strip projecting beyond the surface of said member.

6. A roller for a vegetable cleaning machine comprising an elongated cylindrical member having a spiral peripheral groove therein, a strip of resilient material folded longitudinally upon itself and having the bight portion thereof disposed in said spiral groove and substantially continuously lapped on the bottom thereof, and a securing strand disposed in the bight of the folded strip clampingly securing the same to the bottom of the groove with the sides of the folded strip in supported engagement with the side walls of the groove and projecting therefrom beyond the surface of the cylindrical member.

HERMAN R. HURDELBRINK.
